CLAIM

I claim the ornamental design for a loader for a medication organizer, as shown and described.

DESCRIPTION

FIG. 1 is a front perspective view of a loader for a medication organizer, showing my new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof;

FIG. 6 is a bottom plan view thereof;

FIG. 7 is a rear perspective view thereof;

FIG. 8 is a cross-sectional view thereof, taken generally along lines 8-8 of FIG. 5; and,

FIG. 9 is a cross-sectional view thereof, taken generally along lines 9-9 of FIG. 6.

The broken lines are included for the purpose of illustrating environment and portions of the loader for a medication organizer that form no part of the claimed design.
